UNITED STATES PATENT OFFICE.

HEMAN GARDINER, OF NEW YORK, N. Y.

IMPROVEMENT IN RAILROAD-CAR SPRINGS.

Specification forming part of Letters Patent No. **38,105**, dated April 7, 1863; antedated November 20, 1862.

To all whom it may concern:

Be it known that I, HEMAN GARDINER, of the city, county, and State of New York, have invented certain new and useful Improvements in springs for railroad-cars and other purposes, which I have designated the "Combined Spiro-Elliptic Wool-Packed Car-Spring;" and I do hereby declare the following to be a full description of the same.

The nature of my invention consists, first, in the combination of a semi-elliptic spring, supported at its ends between shoulders on a bed-piece, with a cylindrical metal box arranged over the apex of the spring, so as to sustain the load steadily and uniformly thereon.

And the second part of my invention consists in the arrangement of three or more or less number of spiral springs in a cylindrical metal box, between a cap and bottom plate, having pins in their opposing faces, upon which the ends of the spiral springs are adjusted to keep them in a vertical position, in combination with a semi-elliptic spring arranged upon a bed-piece transversely of the bottom of the cylindrical box.

And the third part of my invention consists in packing the spiral springs contained in a cylindrical metal box with wool, hair, or other similar fibrous substance.

And the fourth part of my invention consists in forming on the upper surface of the cap-plate, covering the upper ends of the spiral springs, a concave seat for the bearings of the truck-plate, so as to allow the car to have an easy fore and-aft vibratory motion upon the springs, and at the same time not jam or bear unequally on them.

But to describe my invention more particularly, I will refer to the accompanying drawings, forming a part of this specification, the same letters of reference, wherever they occur, referring to like parts.

Figure 1 is a plan view of the spring. Fig. 2 is a vertical cut section of the same through the line *x x*, Fig. 1. Fig. 3 is an end side view of the spring. Fig. 4 is a lower face view of the truck-bearings. Fig. 5 is a view of the under side of the spiral springs, cap-plate, showing the ends of the pins on which the upper ends of the spiral springs are secured. Fig. 6 is a view of the upper side of the bottom plate, on which the lower end of the spiral

springs are adjusted on the pins projecting upward therefrom.

Letter A is a bed-plate, upon the ends of which, on its upper face, are formed flanges of metal B, to prevent the semi-elliptic spring C from getting out of place on the bed. Over the middle of the arch of this spring, and resting upon the bed A, is adjusted a cylindrical metal box, D, of such length and diameter as may be required in the construction of the spring. In the lower part of the box D is arranged a metal plate, E, so as to rest loosely upon the apex of the semi-elliptic spring. Letters F are several short pins or studs secured in the upper face of the plate E. On these pins are adjusted three spiral springs, G, which extend upward in length to near the top of the box D, and are held down into it by means of a cap-plate, H, having projecting from its lower face three short pins or studs, I, of corresponding length with those in the bottom plate, E, and which enter into the cavity of the upper ends of the spiral springs. The object of these pins or studs F and I are, first, to steady the spiral springs and keep them in a vertical position; and, secondly, and the more important function required of them, to govern and control the action of the spiral springs with reference to developing the elasticity of the semi-elliptic spring. This is done by making them of such specific length, with reference to the length of the spiral springs, that they will come in contact before the spiral springs have been fully exhausted, and thus relieving them and transferring the load to the semi-elliptic spring, thereby causing a continuous elastic development of power until the whole combination is exhausted.

Letter J is a concave step or seat formed upon the upper side of the cap-plate H, into which rests a semi-cylindrical bearing, K, formed on the lower face of the truck-plate L, the operation of such a device being to allow of a fore-and-aft vibratory motion in the car, without affecting sensibly the vertical pressure of the superincumbent weight upon the spiral springs.

Letter M, as indicated by the yellow-colored parts, represents a packing of wool or hair, surrounding and filling the spaces between the spiral springs and sides of the box in which they are adjusted. This packing is in-

tended to form an elastic support to the spiral springs. The material intended to be used will be combed or carded wool or hair, or otherwise suitably prepared, in which condition it is to be packed by any suitable means firmly into the box and around the springs.

The operation of the spring is that when the load is imposed on the truck-plate the first impression is manifested by the compression of the spiral springs, which are intended to be of sufficient strength to sustain an ordinary loaded car with an easy and delicately elastic vibratory motion, in consequence of the sensitiveness of the spiral springs and the elasticity of the wool packing; but when the load is so great, or the sudden joltings over inequalities of the track cause the studs or pins in the upper and lower ends of the spiral springs to come in contact, the elastic force of the semi-elliptic spring is developed, and thus by the combined action of all the elastic forces a constant and easy elastic vibratory motion is developed to sustain the load.

Having now described my invention and its operation, I will proceed to set forth what I claim and desire to secure by Letters Patent:

1. The use of the semi-elliptic spring supported on a bed-plate between the flanges B, in combination with the box D, arranged and operating substantially as hereinbefore set forth.
2. The use of the plates E and H, having short studs or pins F and I in their opposing faces, as hereinbefore set forth, in combination with the spiral springs G and box D, arranged in operating in combination with the semi-elliptic spring, substantially as hereinbefore set forth.
3. The use of wool, or other fibrous material of a similar nature, packed in a cylinder or box, in combination with the spiral steel springs, for the purposes hereinbefore set forth.
4. The use of the semi-cylindrical bearings K on the truck-plate, in combination with the cap-plate E, working in the cylindrical box D, and resting upon the spiral springs, for the purposes hereinbefore set forth.

HEMAN GARDINER.
